Attorney

UNITED STATES PATENT OFFICE.

JOHN B. BENTLEY, OF JAMESTOWN, NEW YORK.

BOBBIN-SHUTTLE.

1,392,042.

Specification of Letters Patent. Patented Sept. 27, 1921.

Application filed November 8, 1920. Serial No. 422,507.

To all whom it may concern:

Be it known that I, JOHN B. BENTLEY, a citizen of the United States, residing at the city of Jamestown, in the county of Chautauqua and State of New York, have invented certain new and useful Improvements in Bobbin-Shuttles, of which the following, taken in connection with the accompanying drawings, is a specification.

10 The invention relates to shuttles used in looms for weaving; and the improvement consists in providing an exceedingly simple construction for holding a split spindle in the shuttle shell or weft case so that the 15 spindle is held firmly in position when snapped to place in the shell and may be quickly and easily removed or raised for the removal of the spool or bobbin; and the invention consists in the combination and arrangement of the parts as shown in the drawings and hereinafter described and claimed in this specification.

In the drawings, Figure 1 is a top plan view of the shuttle with the spindle in position therein; and Fig. 2 is a vertical sectional view of the same showing the construction and arrangement of the parts. Fig. 3 is a top plan view of the preferred form of spindle removed from the shell. 30 Fig. 4 is an end elevation of the holding clip or bracket for the spindle, said spindle being shown in section within the key-hole shaped open-ended slot into which it is sprung; and Fig. 5 shows preferred views of 35 the holding clip or bracket and the reversible U-shaped spring for tensionally holding the butt of the spindle within the raised end of said holding clip or bracket; and Fig. 6 is a side elevation of said clip or bracket with 40 the U-shaped spring therein in tensional holding position against the end of the spindle, said spindle being shown in the partially raised position; and Fig. 7 is an end elevation of the butt of said spindle. 45 Fig. 8 is a top plan view of the butt end of the shell or weft case with said holding clip or bracket removed showing the crosswise rib and slot therein for one leg of said raised portion of said clip and of said U-shaped spring.

Like characters of reference refer to corresponding parts in the several views.

The numeral 10 designates the shell or weft case which is pointed and tipped at 55 each end in the usual manner and has the central lengthwise slot or bobbin chamber

11 therein for containing the spindle 12 for holding the spool or bobbin.

The slot 11 has the extension groove 13 at one end to receive therein the holding 60 bracket or clip 14, which clip 14 is provided with the raised or inverted U-shaped end 15 which fits over the crosswise holding rib 16 of the wooden shell 10, which rib 16 provides the crosswise slot 17 between the crosswise 65 rib 16 and the end wall of the groove 13. The end leg 18 of the clip 14 and of the reversible U-shaped spring 19 are inserted in said slot 17 over the rib 16 thereby firmly holding said clip 14 and the spring 19 with- 70 in the groove 13. Two screw bolts are preferably provided in the screw holes 20 which firmly fasten the holding clip or bracket 14 in position.

The front end 21 of the clip or bracket 14 75 extends upward and has the key hole shaped open-ended slot 22 therein which opens upwardly so that the spindle 12 can be sprung downwardly into the rounded portion 23 of the same. The slot 22 forms jaws which 80 hold firmly upon the preferably split spindle 12. The split form of the spindle 12 is preferred since it automatically provides the spring holding tension within said rounded portion 23 of the slot 22. The split spindle 85 12 is reversible, that is, either flat side may be placed upward so long as the semi-circular outwardly curved or bowing parts with their outward spring are placed toward each side so that they fit resiliently in- 90 to the round portion 23 of the slot 22 in the upturned end 21.

A hole 24 is provided in the raised portion 15 through which the butt 25 of the spindle 12 fits, pressing against the downwardly extending leg of the spring 19, pressing the same backward toward the cross- 95 wise rib 16 and holding the shoulder 26 on the spindle 12 firmly against the inner wall of the vertical end 21 of said holding 100 clip or bracket 14.

An enlargement 27 is provided on the rounded or outwardly curved side of each of the split portions of the spindle 12 for the bobbin to rest upon and so as to hold the bobbin firmly in position on said spindle 12. The butt portion 25 of the spindle is preferably square and fits in the square hole 24 in the raised portion 15 of the clip or bracket 14. Said body portion has the 110 rivet 28 through the two parts, which parts are curved on their adjacent faces at said

point so that they rock slightly near the bowing spring sides of the spindle and are pressed toward one another as shown in dotted outline in Fig. 3. This rocking freedom of movement at the attaching point at the butt of the spindle by means of the rivet 28, which rivet permits said rocking movement, allows the bowing sides to be sprung inwardly and outwardly with perfect freedom of movement. The square hole 24 and squared butt 25 prevent any turning of said spindle 12, thereby getting out of position or out of the holding clasp within the slot 22.

15 It is now apparent that the spindle 12 can be raised partially or removed entirely from the shuttle to receive the bobbin or spool, and that said spindle 12 can be quickly and easily inserted or pressed downward into the holding position within the spring clip or bracket 14, the upwardly turned jaws of the end 21 of said clip holding firmly against the spool or cap end, and that there are few parts to wear or get out 20 of condition in my improved shuttle.

25 The spindle 12 is made preferably of spring steel semi-circular parts which bow in opposite direction from one another and which are held together preferably at their tip end 29 by the ferrule cap 30 within which said tip ends 29 are firmly attached. The arrangement of the rocking squared contacting ends 25 at the butt of the spindle 12 with the loose rivet 28 extending there-through permits the free springing action 30 of the split spindle parts as shown in dotted line in Fig. 3. The semi-circular-shaped enlargements 27 spring out against the butt of the bobbin, thereby holding the 35 same firmly in position, and the ferrule-shaped cap 30 assists at the other end of the bobbin in holding the same.

40 I claim as new:

1. In a shuttle, a holding clip having a key hole shaped open-ended slot in its upturned end, in combination with a resilient split spindle having a shoulder thereon to spring said spindle into holding engagement against said upturned end and into said 45 open-ended slot, and means for holding the butt of said spindle.

2. In a shuttle, a holding clip having an open-ended slot in an upturned end thereof, a spindle having a shoulder thereon a spaced 50 distance from the butt thereof, to receive and hold the spindle in said open ended slot, and a spring to press against the butt of said spindle with holding tension thereon.

3. In a shuttle, a bifurcated member disposed adjacent to the rear end of the shuttle, a spindle having an abutment thereon to engage the rear of said member, an apertured member to receive the rear end of the spindle, and spring means rearwardly of the 55 apertured member to engage the rear end of

the spindle to force the abutment of the latter into engagement with the bifurcated member.

4. In a shuttle, a bobbin spindle, a holding clip for said spindle having an open-ended key hole shaped slot in an upturned end thereof to receive and hold said bobbin spindle, a square butt and shoulder spaced therefrom on said spindle, said holding clip having a square hole therein to receive said square butt, and a spring to press against said butt of said spindle with holding tension thereon.

5. In a shuttle, a spring holding clip having an open-ended key hole shaped slot in an upturned end thereof, a resilient split spindle adapted to be sprung into holding engagement in said key hole shaped slot, said holding clip having a hole therein to receive the butt of said spindle with holding tension thereon, and a shoulder on said split spindle to bear against said upturned end.

6. A shuttle comprising a shell having a lengthwise bobbin chamber therein, a groove in one end of said bobbin chamber, a cross-wise rib near the end wall of said groove, a spindle holding bracket or clip having a raised end portion insertible over said rib, said bracket or clip attachable in said groove, a U-shaped spring insertible over said cross-wise rib within said raised portion of said bracket or clip, an upturned end on said bracket or clip having an open-ended slot enlarged inwardly to receive the spindle therein in holding engagement, said raised portion having an opening therein for the butt end of said spindle to press against said U-shaped spring.

7. A shuttle comprising a shell having a bobbin chamber with a grooved end, a cross-wise rib in said grooved end of said chamber, a U-shaped holding bracket and spring insertible over said rib in said grooved end, screw bolts for attaching said bracket in said groove in said shell, an upturned end on said holding bracket having an open-ended key hole shaped slot therein, said U-shaped portion of said holding bracket having a square opening therein for the square spindle butt to hold said spindle against turning in combination with a resilient split spindle compressible between the jaws of said key hole shaped open-ended slot to hold said spindle in position, and a shoulder on said spindle to be pressed against said upturned end of said holding bracket by said U-shaped spring.

8. In a shuttle, a split spindle having a loose pin through the parts at the butt of said spindle to permit said parts to rock on one another, a cap ferrule for holding the other ends of said parts of said split spindle, and a holding bracket and spring for locking said spindle in the weft case.

9. In a shuttle, a split spindle comprising

two parts which curve away from one another, means for holding said parts at the tip end of said spindle, means for holding the butt of said spindle with freedom of 5 rocking movement of said parts on one another, said butt having a square shape to prevent turning, a shoulder on said spindle, and locking means adapted to receive said squared butt and shoulder with spring holding 10 tension upon the same.

10. In a shuttle, a split spindle comprising semi-circular outwardly curved parts rigidly attached to one another at their tip end, said semi-circular parts contacting upon one 15 another at the butt of said spindle, a loose holding rivet through said contacting portion to permit said parts to rock upon one another when said parts are compressed and to spring back to the normally bowed position 20 when released from compression, a weft case, and locking means in said weft case to receive and hold said split spindle in locking engagement.

11. In a shuttle, a spindle having an abutment, a pair of spaced vertical arms the rear one of which is perforated to receive the rear end of the spindle and the front one of which is formed to receive the spindle and to allow the abutment thereof to engage the 30 rear face thereof, and spring means associated with the rear arm to engage the rear end of the spindle to thereby force the abutment thereof into engagement with the front arm.

35. 12. In a shuttle, a resilient split spindle comprising two oppositely curved spring parts semi-circular in cross section, the tips of said parts attached to one another by a cap ferrule, the butt portions of said parts 40 contacting upon one another, a loose rivet through said parts permitting their rocking upon one another in the contacting portion at the butt of said spindle, said butt squared

to prevent turning, a shoulder on each part a spaced distance from said squared butt, enlargements on the outer sides of said parts a spaced distance from said shoulder to rest 45 the bobbin butt thereon, a weft case having a groove therein, a locking clip attached in said groove having a squared opening to receive 50 said square spindle butt, an open-ended key-hole-shaped slot to spring said split spindle thereinto in holding engagement, and a spring in said holding clip bearing against said square spindle butt to press said shoulder against a portion of said holding clip 55 with spring tension.

13. In a shuttle, a bifurcated member, a spindle having a pair of oppositely disposed curved spring members, means spaced from 60 the rear ends of said members to loosely connect the same, and a perforated member formed to receive said rear ends of said members, said bifurcated member being formed to engage said members in front of 65 the rear ends thereof so as to compress same and thereby cause the rear ends to be expanded against the walls of the perforation of the perforated member.

14. In a shuttle, a spindle having a pair of 70 oppositely disposed curved spring members, means spaced from the rear ends of said members to loosely connect same, a holding member formed to engage said rear ends of the members, and means to engage said 75 spring members to compress the same in front of said connecting means thereby to cause expansion of the rear ends thereof into engagement with the holding means.

In testimony whereof I have affixed my 80 signature in the presence of two witnesses.

JOHN B. BENTLEY.
